UNITED STATES PATENT OFFICE

HARRY SADJIAN, OF PHILADELPHIA, PENNSYLVANIA

TOOTHPICK DISPENSING DEVICE

Application filed March 15, 1930. Serial No. 436,019.

This invention relates to tooth pick dispensing devices, and particularly to that kind thereof which are adapted to project one tooth pick at a time, and upward from said device.

Tooth picks, particularly those made of wood, when put into a shallow dish to be picked up by a user, are subject to dust and the contact of soiled fingers, besides such a way of serving tooth picks is wasteful as well as unsanitary, inasmuch as more tooth picks are taken up at one time than are usually needed, for a person can only use one at a time.

15 It is therefore the main object of my invention to provide a device adapted to hold tooth picks vertically and manually operate to project one tooth pick, upwardly protruding from the device, at a time, by pushing in a button, preferably at the side of the device.

Another object of my invention is to provide a tooth pick dispensing device, having a simple and easily operated construction, and one which by its form of construction 25 easily lends itself to the usual methods of manufacture for quantity production at a comparatively cheap cost.

Another object is to provide a dispensing device for tooth picks which can be embodied in a slender and well formed casing which will blend in style with the usual set 30 of table ware.

A further object is to provide in a device 35 for dispensing tooth picks, a storage chamber in the top thereof, adapted to hold the picks upright resting upon a conical floor within the chamber, so that the picks will gravitate toward a hole in the center of the floor, the hole being of such a diameter that 40 only one pick will lodge therein at a time, and register with a plunger upon which the single tooth pick rests, having mechanism below for operating the plunger to force out the tooth pick from the number occupying 45 the storage chamber. I also desire to guide the pick automatically in its upward travel, so that by reason of the particular formation of the cap of the device, the upper end of the projected pick will work its way toward the center of the top of the cap and

thru a hole therein, projecting in its completed upward travel just enough to be easily taken hold of by the thumb and finger and completely withdrawn.

With these and other objects which will 55 hereinafter appear, my invention resides in certain construction, one embodiment of which is illustrated in the accompanying drawing. The construction therein shown is described below, the operation being explained and what I claim is set forth.

In the drawing,

Figure 1 is a sectional elevation of a tooth pick device for dispensing one tooth pick at a time, and embodies my invention.

Figure 2 is an elevation of the operating means shown in Figure 1, looking into a different side thereof.

Figure 3 is another elevation of the said operating device, looking into the side opposite to that shown in Figure 2.

Figure 4 is a top plan of the frame and assembled parts therewith, which are shown in the other figures in different views thereof.

Figure 5 is an elevation in section of the 75 upper part of the plunger rod, showing the hollow cup shape of the top of the rod for engagement with the central tooth pick of the bunch within the storage chamber.

In the figures, the tapered casing 10 is 80 shown to be flared at the base 11, which has an offset 12, forming a seat 13, up against which the circular base plate 14 is held by the screw 15. The edge 16 of the base 11, forms a footing for the device. At the upper 85 end of the casing 10 is formed a thread 17 adapted for screw threaded engagement with the cap 18, which has a downwardly diverging inner wall 19. In the top of the cap 18 is a central hole 20, of a size to permit only 90 one tooth pick to be protruded therethru, at a time.

Fitting within the casing 10, and midway of its height, is a conical member 21, having its upper face formed into a hopper 22, terminating in a hole 23, of a size to permit of only one tooth pick at a time to lodge therein. Between the member 21 and the base plate 14, and fixed to both member 21 and plate 14, is a frame 24, which is shown made of sheet 100

material, having two upright and parallel sides 25 and 26, with two spacing plates 27 and 28 integral therewith, and positioned, respectively, at the top and the bottom of the frame 24. Journalled in the sides 25 and 26 of the frame 24, are the three small shafts 29, 30 and 31. On the shaft 29 is fixed a small annularly grooved pulley 32, while on the shaft 30 is fixed a comparatively larger grooved pulley 33. Engaging the grooves of these pulleys is shown a small chain 34, fixed at 35 to the pulley 33. The inner length of chain 34, between the pulleys is vertical and parallel with the plunger rod 36, and is fixed at 37 to the rod 36. The lower part of the rod 36 is fixed to a sliding member or block 38, having two sets of fingers 39 and 40, on each side of the block 38. Between the set of fingers 39 and 40 on one side of the block 38 is the guideway 41, and between the set of fingers 39 and 40, on the opposite side of the block 38 is the guideway 42, parallel with the guideway 41. These guideways 41 and 42 are parallel and fixed at their ends to the member 21 and the base plate 14.

Upon the shaft 31 is fixed the segmental gear 43, having teeth 44, meshing with the small gear 45, which is fixed upon the shaft 28, with the larger pulley 33. Also fixed upon the shaft 31 is a cam finger 46, which extends outward and downward into contact with the inner end of the pusher rod 47, and has a position directly behind the rod 36, so that the pusher rod comes in a radial position with respect to the formation of the conical casing 10. The pusher rod 47 has a knob 48, and is journalled within the cylindrical block 49, which is fixed to the casing 10. A wire spring 50 encircles the shaft 31 along side of the segmental gear 43 and has its end 51 bearing against the plate 27, and its lower end hooked at 52 upon the segmental gear 43.

Relative to the operation of the above described device, assume that a quantity of tooth picks 53 have been put into the chamber 54, and that the cap 18 has been screwed on in the place shown in Figure 1. The tooth picks 53 will then have their lower ends resting upon the inclined surface of the hopper bottom 22, the inclination of which should be sufficient to have the lower ends of the tooth picks slide naturally together, although a few to the right in the drawing are shown apart to illustrate them separately. One of the bunch of tooth picks will gravitate into the hole 23, which is a little larger than the end of the tooth pick, but too small to admit of two at a time. The tooth pick resting in the hole 23, upon the cup end 36^a of the plunger rod 36, is numbered 55. Now, upon pushing in the rod 47, the cam finger 46 is forced inwardly, turning the shaft 31 and the segmental gear 43 clock-wise, as seen in Figure 1. This turning of the gear 43 clock-wise is against the down pressure exerted by

the spring 50 upon the gear 43. The gear 45, in mesh with the gear 43 then turns counter clockwise, as does the pulley 33, fixed on the same shaft 30, upon which the gear 45 is fixed, and the inclined part of the chain 34 between the pulleys 32 and 33, is pulled downward, pulling up the vertical side of the chain 34, and the rod 36, attached thereto, with the sliding block 38. The rod 36, in sliding engagement at its end 36^a with the hole 23, lifts up the tooth pick 55, resting upon it, so that the upper end of the tooth pick 55, coming into contact with the converging inner wall 19, of the cap 18, is guided into the hole 20, thru which the tooth pick 55 passes, coming to a stop at 55^a, as shown in Figure 1, when the pusher rod 47 has reached its inmost limit, and the tooth pick 55, having reached the limit of its upward travel, remains in that position as the rod 47 is released, and the action of the spring 50, returns the parts to their normal position. As the plunger rod 36 drops away from contact with the tooth pick 55, the other tooth picks close in at their lower ends and frictionally bind against the lower end of the tooth pick 55, causing the latter to stay up projecting out of the cap 18. When the tooth pick 55, in its upmost position 55^a is withdrawn by the thumb and finger of the user, another tooth pick gravitates into the hole 23, upon top of the plunger rod 36, ready to be pushed out when the knob 48 is pushed inwardly, for a repetition of the ejecting operation. I have found when using my model, made as illustrated and described above, that a sudden and forceful push on the knob 48, causes the tooth pick to jump out clear of the device.

When the last tooth pick of the bunch has been projected, the cap 18 can be unscrewed and a new supply of tooth picks put into the storage chamber 54, and the cap 18 screwed back in place.

This construction of dispensing device lends itself to the slender tapering shape of the casing, and makes for a neat appearance, resembling somewhat in shape the saltcellar for table use. The parts of the device are comparatively few and most of them can be stamped out of sheet metal.

Inasmuch as changes in the construction of the device herein shown in the one embodiment of the same can be made without departing from the spirit and scope of my invention, I wish to include all modifications which come within the purview of the appended claims.

I claim,

1. In a tooth pick dispensing device adapted to eject one tooth pick longitudinally and vertically at a time, and having a plunger for ejecting said tooth pick, a frame, two sprocket wheels journaled in said frame, one of said wheels being smaller than the other,

the smaller of said wheels being uppermost, a sprocket chain engaging said wheels, said chain being connected with said plunger, and means for actuating said wheels to move said chain manually.

2. A tooth pick dispensing device adapted to project one tooth pick at a time from a bunch of tooth picks contained therein, comprising a casing, an upright storage chamber 10 in the upper part of said casing, a conically formed cap removably attached to the top of said casing, having an inclined and upwardly converging inner wall terminating in a hole at its apex, a hopper bottom to said 15 chamber, terminating below in a hole, into which a single tooth pick is adapted to gravitate at its end, a plunger rod positioned for vertical reciprocation in said hole, of said hopper bottom, and reciprocating means for 20 operating the said plunger rod, comprising a frame below said hopper bottom, three shafts journaled in said frame, one of said shafts being above and parallel to another of said shafts, a pulley on each of the two last mentioned shafts, said pulleys being in the same plane, a chain or the like as a belt engaging 25 said pulleys, said chain being fixed to the lower part of said rod, a guiding means for said rod for keeping it in line with its axis 30 during its reciprocation, a gear fixed on the same shaft with the lower of said pulleys, a larger gear upon the third shaft, in mesh with the previous gear mentioned, and means extending outside said casing adapted to 35 rotate said gears.

HARRY SADJIAN.
